UNITED STATES PATENT OFFICE.

JOSIAH WARD CHILDS, OF BOSTON, MASSACHUSETTS.

IMPROVEMENT IN TOY REPEATING PISTOLS.

Specification forming part of Letters Patent No. 174,779, dated March 14, 1876; application filed January 31, 1876.

To all whom it may concern:

Be it known that I, JOSIAH WARD CHILDS, of Boston, Suffolk county, Massachusetts, have invented a Toy Repeating Pistol, of which the following is a specification:

This invention is a toy, for the use of children, for shooting peas or other round pellets, my object being to produce, at small expense, a toy which shall possess the great attraction of being a repeating or magazine pistol, or one capable of discharging a succession of pellets without reloading, and the invention consists in the combination of certain co-operative mechanical devices, whereby, upon pulling the trigger, a pellet is dislodged from the magazine and impelled forward through the barrel, with a sudden thrust from a spring-impelled ejector, the whole being substantially as hereinafter described.

The drawings accompanying this specification represent, in Figure 1, a vertical and longitudinal section of a pistol embodying my improvements, while Fig. 2 is a horizontal section of the same. Fig. 3 is a perspective view of the ejector and retractor, to be explained. Figs. 4 and 5 are sections representing modifications of the invention, to be hereinafter explained.

In these drawings, A represents the stock or frame, which receives the operative mechanism, while B represents the handle and C the barrel, the bore of the latter being shown at D.

Within the upper part of the stock A, and somewhat above the level of the bore of the barrel, I create a channel, E, the outer end or mouth of which is closed by a gate, F, to admit of ready insertion of pellets, and whose inner end terminates in a short downwardly-projecting bend, G, the bottom of which coincides with the rear end of such bore, the channel E being, preferably, somewhat higher in rear than in front, and the whole being so arranged that a pea or round pellet being introduced into said channel from its outer end will, if unobstructed, roll down the inclined plane to and through the vertical branch G, and present itself to the rear end of the bore D.

Immediately below the channel E, I dispose

what may be termed a pair of forceps, a^1 , composed of two delicate twin-springs, $a^2 a^2$, secured at their bases within a recess, b^2 , created in the stock A, the forward and free ends of these springs terminating at a point immediately in rear of the barrel, and being at such a distance asunder as to intercept, with a delicate pressure or friction, the first pellet of the series within the magazine and prevent the accidental escape of this pellet while the ejector is being drawn back.

J, in the drawings, represents the ejector for expelling the pellet through the barrel, such ejector being composed of a bell-crank lever, which is situated immediately in rear of the rear end of the barrel, and pivoted at its lower part within a recess, K, formed in the lower part of the stock A, the upright arm L of this lever intercepting the bore of the barrel, while its lower arm N extends rearward, and constitutes the means whereby the movements of the arm L are effected, the fulcrum of the crank J being shown at O as a horizontal pin, passing through such crank and the lower part of the stock.

P, in the drawings, represents a retractor for actuating the ejector, composed of a T-shaped piece of metal playing within the rear part of the recess K, and pivoted upon a horizontal pin, Q.

The lower end R of the retractor P constitutes the trigger of the pistol, while its horizontal arm c operates, in connection with the arm N of the ejector J, to bear down such arm N and retract the arm L. The arm L of the ejector J is forced forward closely up to the rear end of the barrel C by a spring, S², arranged in front of such ejector within a pocket, T, in the lower part of the stock A, while the arm c of the retractor is forced upward by a spring, U, arranged as shown in Fig. 1 of the drawings.

The operation of the above mechanism is as follows: the parts standing in the respective positions shown in Fig. 1 of the drawings, and the magazine E, containing a number of pellets, the innermost one, d, of such pellets resting upon the top of the ejector L, the top of which is preferably sloping, in order that a pellet resting upon it may, if left with-

out restraint, roll into the barrel, rather than rearward into the mechanism behind the ejector.

A pull upon the trigger R lowers the arm c, and this arm, in its descent, abuts against and lowers the arm N of the ejector J and retracts its upper arm L against the stress of the spring S² to such an extent that, as the arm reaches its extreme rearward position, the pellet d is left free and drops into the bottom of the branch-channel G and into the embrace of the forceps a¹, the outer ends of the arms a² of the latter serving, as before stated, to exercise a gentle restraint upon such pellet, or offer a slight resistance to its forward movement, sufficient to retain it in place for an instant, it being understood that as fast as one pellet drops those behind advance a like distance. The pull upon the trigger is continued until the arm L is forced to the rear of the pellet d, as stated, when the arm c passes below the arm N of the ejector J, and the arm L of the latter is impelled suddenly forward by the stress of the spring S², and in its progress intercepts the pellet d and expels the latter violently through the barrel, the forceps a¹ offering but slight resistance to the forward motion of the pellet, when the latter is struck by the arm L.

As the hold upon the trigger is released, the arm c is returned to its original position, in its ascent passing by or behind the arm N, the contiguous faces of the two being beveled to permit of such passage. It will thus be seen that a pull upon the trigger releases and expels from the barrel a pellet from the magazine, and this movement may be repeated in rapid succession until the magazine is exhausted.

It requires but a very short space of time to replenish the magazine, by dropping the pellets into it through its rear end. The magazine E may be of various forms, and the pellets, in lieu of rolling or passing toward the barrel by their own momentum, may be impelled by a spring; but I prefer the arrangement herein shown.

The above combination of mechanical devices embraces means whereby I have carried out the object I have in view, and I would state that I do not confine myself strictly to this precise mechanism, as the same may be varied to considerable extent without losing sight of the novel features of my invention. For instance, I have shown in Fig. 4 of the drawings a modified arrangement of the principles of my invention, in which the stock or frame is represented at A⁴, the handle at B⁴, the barrel at C⁴, and the bore of the latter at D⁴, while the channel or magazine for containing pellets is shown at E⁴.

H³ in the drawings represents a spring-latch secured horizontally within a channel, I³, created in the stock A⁴, immediately below the channel or magazine E⁴, the rear end of this latch being secured to the stock, while its forward end is allowed sufficient lateral play to

be pushed to one side of the axis of the magazine to such an extent as to allow a pellet to pass from the latter into the branch G, it being observed that the free end of the latch terminates in a thin plate or shelf, a, which constitutes a gate to close communication between the magazine and barrel and hold back the pellets contained in such magazine. The natural and normal position of the latch is that last described, and it is maintained in this position by its own inherent elasticity, or by other suitable pressure.

J³ represents an upright ejector for discharging or expelling the pellet through the barrel, this ejector being in the present instance simply a wire, disposed within a chamber, b³, created within the stock A⁴, immediately in rear of and intercepting the bore of the barrel, and being impelled forward closely up to such bore by its own stress.

K³ in the drawings represents a retractor, composed of a horizontal bar playing within a groove, b³, created in the stock A⁴, below and parallel with the channel I³; this retractor, like the latch H³, being susceptible, at its front end, of horizontal play within its groove, but in an opposite direction, and turning upon its rear end as a pivot, a suitable spring, d³, being employed to drive the retractor forward bodily and to force its free end in a lateral direction toward the bore of the barrel, and so that a hook, e³, upon its front end shall engage the ejector J³, the inner side of the nose of this hook being sloping, in order to ride over the ejector, as hereinafter stated. The retractor K³ is pulled backward by a trigger-lever L³, which is disposed within the rear part of the chamber b³, and with its finger portion f³ protruding below the stock A⁴, such trigger-lever being pivoted near its upper end upon a pivot, g³, and passing through a notch, h³, cut in the retractor K³, the extreme upper end or nose i³ of such trigger-lever being situated closely in rear of and so as when moved forward to intercept a sloping spur, k³, formed upon the rear lower part of the latch H³.

The operation of the above mechanism is as follows, the parts standing in the respective positions shown in Fig. 4 of the drawings, and the magazine E⁴ containing a number of pellets, the innermost one resting upon the nose of the gate H³: A backward pull upon the trigger results as follows—the retractor K³ is first acted upon by such trigger directly and pulled backward a short distance, carrying with it the upper end of the ejector J³, when the nose i³ of the trigger-lever L³ wipes against the sloping spur k³ of the gate H³ and begins the lateral movement of the forward end of the latter, which finally results in uncovering or opening the outlet of the magazine, these movements of the trigger, ejector, and gate continuing until the trigger has nearly reached its extreme rearward movement, and the forward or free end of the gate

has receded from under the outlet of the magazine, and a pellet has dropped into the branch-channel G and presented itself before the rear end of the bore of the barrel.

The trigger is now pulled back a short additional distance, which brings it to its extreme position in this direction, and as it reaches this limit the hook e³ of the retractor K³ loses its hold of the ejector, and the latter, by its inherent force, is suddenly driven forward and intercepts the pellet, expelling the latter through the barrel with great force, while immediately prior to this release of the ejector the nose i³ of the trigger passes beyond the spur k³, and the gate H³ returns to its normal position. The respective movements of the gate H³ and ejector J³ are so adjusted or timed that immediately upon the release and descent of a pellet from the magazine the ejector flies suddenly forward in order to intercept such pellet before it can escape into the bore of the barrel, and the adjustment also provides, as before stated, for the return of the gate to its original or normal position immediately before the flight of the ejector takes place, in order to interpose a barrier between the released pellet and those behind it before such released pellet is expelled by the ejector, as otherwise the next succeeding one behind would be caught and injury result. To enable the position of the gate H³ to be readily adjusted, it should be formed with a short longitudinal slot, a³, through which the confining-screw b³ passes.

As soon as the pellet has been expelled, as stated, the hold upon the trigger is removed or relaxed, and such trigger returns to its original position by the power of the spring d³; consequently the retractor, by the same power, is forced forward or returned to its original position also, its hook riding over the ejector J³ in the act, and settling behind and engaging the latter, while the nose i³ of the trigger lever passes behind and to the rear of the spur k³ of the gate H³, as shown in Fig. 4 of the drawings.

I claim—

1. In combination with the stock and barrel of a toy pistol, the following elements, namely:

First, an inclined or other proper magazine for containing a supply of pellets, which are fed toward the barrel in a suitable manner; second, a swinging lever or its substitute for holding the supply of pellets within the magazine, and for expelling the lowermost or advance one of such pellets; and, thirdly, of a pair of forceps, operating in connection with the barrel and ejector, to retain said lowermost pellet until the same is struck and expelled by said ejector, the latter being retracted by the trigger, and impelled forward by a suitable spring, and the whole operating substantially as and for purposes stated.

2. In combination with the magazine E⁴, the gate H³, with its lateral movement, serving to retire and release a pellet and suddenly return and interpose itself between the pellet thus released and those behind it, substantially as and for purposes stated.

3. The combination of the ejector J³, retractor K³ or its substitute, and trigger L³ with the magazine E⁴, and barrel C⁴, and the gate H³ or its equivalent, substantially as and for purposes stated.

4. In combination with the magazine E and forceps a¹, the ejector J, intercepting the bore of the barrel, when constructed and arranged to operate substantially as and for purposes stated.

5. The combination of the spring-impelled ejector J, intercepting the barrel, as stated, and retractor P, under such an arrangement that, by a rearward pull of the trigger, the retractor retracts the ejector until the latter reaches a given point, when the retractor loses its hold upon the ejector and the latter is shot forward, substantially as and for purposes stated.

6. The construction and combination of the trigger-lever P and ejector J, substantially as herein described, whereby a complete backward pull upon such trigger results in a retraction and forward movement of the ejector, essentially as and for purposes stated.

J. WARD CHILDS.
